CLAIM

The ornamental design for a ceiling fan balance corrector, as shown and described.

DESCRIPTION

FIG. 1 is a front elevational view of the ceiling fan balance corrector showing a use of my new design; FIG. 2 is an enlarged rear elevational view thereof; FIG. 3 is an enlarged left side elevational view thereof; FIG. 4 is an enlarged right side elevational view thereof;

FIG. 5 is a greatly enlarged top plan view thereof; and, FIG. 6 is a greatly enlarged bottom plan view thereof. The broken-line showing of a ceiling fan in FIG. 1 is for illustrative purposes only and forms no part of the claimed design. The stippled shading in FIG. 6, represents an adhesive surface and is understood to extend throughout the area represented.
